UNITED STATES PATENT OFFICE.

FRANCIS H. RICHARDS, OF SPRINGFIELD, MASS., ASSIGNOR OF ONE-HALF
TO THE PRATT & WHITNEY COMPANY, OF HARTFORD, CONN.

MACHINE FOR COUNTING, PACKING, AND BANDING ENVELOPES.

SPECIFICATION forming part of Letters Patent No. 340,243, dated April 20, 1886.

Application filed June 10, 1884. Serial No. 134,480. (No model.)

To all whom it may concern:

Be it known that I, FRANCIS H. RICHARDS, a citizen of the United States, residing at Springfield, in the county of Hampden, State of Massachusetts, have invented certain new and useful Improvements in Machines for Counting, Packing, and Banding Envelopes and Similar Articles, of which the following is a specification, reference being had to the accompanying six sheets of drawings, forming a part thereof.

This invention relates to machinery for the counting and packing of envelopes, cards, papers, and similar articles into bunches of a given number and to the banding of the said bunches.

It has for its object to furnish mechanism adapted to take envelopes—or other articles, as the case may be—as they are delivered from the usual envelope or other machines, to automatically count, pack into bunches, (in the case of envelopes usually of twenty-five each,) and to put bands on the said bunches, ready for boxing.

It consists in certain combinations of mechanism, which will first be described as when adapted for counting, packing, and banding envelopes in connection with the drawings, and then specifically pointed out in the claims.

Referring to the drawings, Figure 1 is a plan view of a machine embodying my invention for counting, packing, and banding envelopes. Fig. 2 is a side elevation of the same. Fig. 3 is a vertical transverse section in line X X, Figs. 1 and 2. Fig. 4 is an enlarged

plan view of a part of Fig. 1, and Fig. 5 is an elevation showing the same parts as are shown in Fig. 2 and upon the same scale; Fig. 6, a view in elevation, taken in line Y Y, Fig. 1, of the parts shown in Figs. 4 and 5, which figures are both drawn in projection thereto. Fig. 7 is an enlarged plan view of the counting mechanism; and Fig. 8 is an elevation of the same, partially in section, drawn in projection to

Fig. 7. Fig. 9 is an enlarged plan view of another part of Fig. 1; and Fig. 10 is an elevation of the same in projection thereto. Fig. 11 is an enlarged vertical longitudinal section of the driving mechanism, the same parts being also shown in Figs. 1, 2, 3, 4, 5, and 6.

Fig. 12 is a plan view, partially in section, of a part which is called the "shuttle," and Fig. 13 is an elevation of the same. Fig. 14 is an enlarged sectional view of a part of Fig. 12. Fig. 15 is a cross section in line c d, Figs. 12 and 13. Fig. 16 is a cross-section in line e f, Figs. 12 and 13. Fig. 17 shows four views in projection of the "wedge" of the shuttle. Figs. 18 to 25, both inclusive, illustrate the various positions of the shuttle during the operation of the machine. Fig. 26 shows a part of Fig. 1 with mechanism for operating plunger J.

Similar letters refer to similar parts throughout the several views.

A, Figs. 1 and 2, is a portion of the frame of an envelope-machine or other suitable bed for receiving the pieces which carry the operative parts of the machine.

A² is the frame of the banding-machine proper, secured to bed A, which has ways for a shuttle-slide, and a number of bearings, substantially as shown, for shafts, studs, and a cutter-carrying ring.

A³ is the frame of the counting mechanism, forming also with the aid of the plunger D the box Q, Figs. 1 and 7, into which the envelopes are packed as they are counted. The envelopes are delivered from any suitable envelope-folding machine into the box at N, Fig. 8, being directed thereto by suitable guides, (not shown,) which belong to said folding-machine, from which point they are driven into the box at N² by any suitable plunger or follower.

D represents such a plunger or follower, which also belongs to and is operated by the folding-machine, and is shown in its two extreme positions in Fig. 8, in one of which it is represented by solid lines and in the other by dotted lines. In the latter position it forms one side of the said box.

I are hooks, which are pivoted to frame A³ for the purpose of keeping the envelopes from leaving the box by the entrance when once they are driven into it. It is not necessary that these hooks should be of any particular construction so long as they serve the purpose specified, and such as now used for similar purposes are generally suitable. One of

these hooks—preferably the one shown in Figs. 7 and 8—is provided with a pallet, I², acting to let off the escapement-wheel I³, which is driven from shaft S³ by means of gear G 5 on said shaft and pinion G² on said escapement-wheel. Shaft S³ is preferably driven by means of some suitable friction device, which, as herein shown, consists of a friction-belt, B, which runs from some constantly-revolving 10 pulley, as P', on the driving-shaft to the pulley P, which is fixed on said shaft S³, said belt being only tight enough to convey the necessary amount of power to the escapement mechanism. This belt, being thus driven, acts 15 through the gearing shown to keep the escapement-wheel constantly pressing upon the pallet. Then when the plunger D pushes forward an envelope from N to N², the said envelope lifts the hook carrying the pallet, and thereby allows 20 the escapement-wheel to turn forward one-half of one division, the falling of the said hook after the passage of the envelope allowing it to turn the remaining half of that division.

25 W is a stop-wheel, which is carried upon shaft S³. The object attained by the escapement mechanism above described is to connect any suitable lever or equivalent part, as the arm or hook I, to this stop-wheel in such a 30 manner that each envelope entering the box will cause the wheel to turn forward a fixed amount, which, as herein shown, is intended to be the one seventy-fifth part of a circle. The said wheel is divided by notches V into three 35 parts, each representing the packing of twenty-five envelopes, that being the number usually packed into one bunch. Whenever other sized bunches are to be made, this wheel and the escapement-gearing should be correspondingly 40 constructed. This wheel has been described as a "stop-wheel" because its office is to "stop" a plunger from driving the envelopes out of the box Q, except at those times when one of the notches V comes to a 45 given position.

J is a plunger or slide, which is adapted to be reciprocated within the slide-case J² (see Figs. 1 and 2) by suitable connections, herein-after described, from the envelope-folding machine, these connections being such as to move 50 said slide toward the right hand, as seen in Figs. 1 and 2, by a positive movement, and toward the left hand by a spring movement. The extreme end of this plunger, which enters 55 the box Q, is made to fill the said box closely, so that when said plunger makes its stroke toward the left hand, as in Fig. 19, it can drive out of that box all the envelopes packed therein. Throughout the rest of its length 60 this plunger is made smaller than at that end, (see Fig. 8,) and has a rib, J⁴, formed thereon fitted to slide through the notches of stop-wheel W. When the slide is at its extreme right-hand position, (see Figs. 1, 7, and 18,) 65 the end of this rib stands close to the right-hand side of that wheel, so that said wheel may be revolved, as above described. A de-

vice consisting of lever L, supported upon a stud, J⁵, a pin, J', on slide J, for actuating said lever, and a rod, R, connected to said lever, 70 is provided for the purpose of allowing the cam-shaft S² of the banding mechanism to start at the moment when the packed bunch of envelopes is driven out of box Q by slide J into the tubular box T, which is prepared to receive them, as hereinafter further described. During the operation of the envelope-folding machine, to which this counting and packing mechanism may be attached, owing to the connection from said machine to slide J being 80 in some way made suitable therefor, the said slide J is, at each revolution of said machine, moved toward the right far enough to clear the stop-wheel W, for the purpose of allowing that wheel, through the action of the escapement mechanism, to be revolved through the predetermined fixed distance above referred to. When the stop-wheel has been so moved, the said slide is allowed to commence its stroke toward the left hand, as seen in Fig. 1, when 90 it either rests against the side of that wheel, being thereby prevented from entering box Q, or, if that wheel has arrived at the proper position therefor, the rib J⁴ thereof passes through the notch V and allows the said slide 95 to make a stroke from its position in Fig. 18 to its position in Fig. 19, this stroke taking place during the period of time while the plunger D stands in the position shown by dotted lines in Figs. 7 and 8, and being made, preferably, by a spring, as before mentioned.

In Fig. 26 I have shown in plan view mechanism substantially such as I now use for actuating plungers D and J. This mechanism is driven from shaft 3, which is the main cam-shaft of an envelope-machine. On said shaft are fixed two cams—4 for driving plunger D and 5 for driving plunger J. Cam 4 acts upon a roll, 6, fixed to a rod, 7, which is connected to the plunger D, and imparts thereto 105 a reciprocating motion through its bearing 8. Cam 5 acts upon a roll, 9, fixed to lever 10, which lever is pivoted at 11 to bracket 12, fixed on bed A. Said lever 10 is thus moved in one direction by cam 5, while spring 13 115 moves it in the opposite direction.

Plunger J is connected to lever 10 by a simple link, 14. The lever 10 is shown in its outward position by dotted lines, being thrown outward by cam 5 and inward by spring 13. 120 An ordinary spring is to be provided (not shown in the drawings) for moving slide D, so as to keep roll 6 against cam 4.

It will be understood that cams 4 and 5 are to be so shaped as to impart the requisite 125 movements to the plungers at the proper times to operate them in harmony with the other parts of the machine.

Thus far in this specification I have only described those parts which constitute the counting and packing mechanisms, which mechanisms serve to prepare the envelopes for and to deliver them to the banding mechanism, this being the principal mechanism, to which the 130

others are merely auxiliary. This banding mechanism I will now describe, first premising, however, as every mechanic will understand that some suitable—which may be any 5 suitable—operative mechanism may be and is to be provided for performing the various movements enumerated of the parts which are now to be described.

M is the frame or "body" of a part of the 10 machine, which I call the "shuttle," and which is the principal part of the banding mechanism. This shuttle terminates at its right-hand end in a tube, T, for receiving the bunch of envelopes from box Q, having a rectangular 15 cross-section corresponding, approximately, to that of box Q, and at its left-hand end in a wedge, W', Figs. 13 and 17.

In order to make the body of the shuttle as light as consistent with the strength required, 20 and to provide room for the operative parts contained therein, it is made of a trough-shaped form. (Shown best in Fig. 16.)

Within the tube T, which is usually made 25 of tool-steel, is a piston, T', fitting it closely, and adapted to slide throughout the whole of said tube, which is beyond the frame M, for the purpose of pushing a bunch of envelopes out of said tube. Extending toward the left hand from said piston are two bars, T², which 30 are provided with a friction-roller, R², running against the frame M, and with two driven rollers, R³—not touching R²—between which the reciprocating driving-roller R⁴ operates to impart a similar motion to bars T², and through 35 them to piston T'. The stroke of this roll R⁴ is represented by line Z Z, Fig. 12, the said roller being carried in a suitable slide or its equivalent. (Not there shown.) The manner in which the bars T² are driven by that roller 40 is analogous to the manner in which a loom-shuttle is driven by similar rollers, as illustrated in United States Patents No. 80,982, dated August 11, 1868, and No. 133,868, dated December 10, 1872, to which reference may 45 be had. The object of using this peculiar driving device is to allow the shuttle to be enclosed within a tube, of paper or of other suitable material, from which the bands are to be afterward cut off without interfering with the 50 reciprocation of the piston T'. The said tube being flexible, in passing between rollers R³ and roller R⁴ offers no resistance to that motion, except to cause all three rollers to turn upon their pivots.

55 The entire shuttle is supported between two sets of four rollers each. One set of these, near the middle of the shuttle, are geared together, as shown best in Fig. 3, and are the feeding-rollers for feeding a tube of paper 60 over the shuttle, which they also hold in position. The other set, near the left-hand end, as seen in Figs. 1, 12, and 13, are merely idler-rollers for steadyng the shuttle, there being enough space between them and the shuttle-body to permit the free passage of the tube of band material.

M² is the shuttle-slide, which is gibbed to

bed A² by gibbs D², and is provided with two vertical frames, N³ N⁴, one at each end thereof. Suitable operative mechanism is provided, 70 as hereinafter described, for imparting to this slide a reciprocating motion. The frame N³ is provided with lugs for holding the pivots of the set of four steadyng-rollers, R⁵, of which one is above, one below, and one on 75 each side of the shuttle. The frame N⁴ is provided with bearings N⁵ for the shafts N⁶ of the feed-rollers R⁶, the said shafts N⁶—four in number—being geared together by three pairs of bevel-gears, G⁸. (Shown in Figs. 1 and 2 and 80 shown best in Fig. 3.) Some one of those shafts, in this instance the lower one, is provided with a ratchet-wheel, R⁷, which is acted upon by a pawl, J⁵, pivoted at J⁶ to a bracket, B², that is secured to one of the gibbs D². These 85 parts are shown best in Figs. 3, 9, and 10. It should be noted that when constructed as herein represented the pawl J⁵ works in a fixed position in the machine, and that the ratchet-wheel R⁷ is carried with the slide M², 90 so that at the latter part of its left-hand stroke, when in about the position shown by dotted lines in Fig. 10, one of its pins strikes the said pawl J⁵, turning said wheel through one division, as shown in said figure, thereby 95 turning also all of the feed-rollers R⁶, carrying forward whatever paper or other sheet material which may be between them and the shuttle. The feed-rollers R⁶ do not touch the body of shuttle M, but they run against other 100 rollers which are placed within spaces formed in the shuttle-body. The arrangement of these other rollers is shown in Figs. 12, 13, 14, and 15. At the upper and lower edge of the shuttle-body, and at one side, at the right hand in 105 Fig. 15, there is in each place a single roller, R⁸. At the other side, at the left hand in Fig. 15, there are two rollers, R⁹, which are situated relative to their roller R⁸, similarly as the rollers R³ are situated relative to their driving-roller 110 R⁴, and for a similar purpose, as hereinbefore described. By means of these two rollers R⁹ one of the feeding-rollers R⁶ not only acts in conjunction with the others to support the shuttle in a fixed vertical and lateral position 115 and to feed a sheet of paper, but it also acts, by reason of its position, partially between said rollers R⁹, as shown in Fig. 14, to control the longitudinal position of said shuttle.

It will now be obvious from the drawings, 120 the references cited, and the preceding description how the said shuttle is entirely supported upon and by a system of rollers; how the piston T' can be operated while the shuttle is wrapped in a sheet of paper, and how 125 that paper may be fed through between rollers R⁶ and rollers R⁸ and R⁹, while the position of the shuttle itself remains unchanged. The object sought to be attained by so constructing the shuttle and the other mechanism described 130 as to secure those results is to permit the use, for the making of envelope-bands, of a tube of paper previously prepared, which may be fed over the said shuttle, and thereby over the

bunch of envelopes therein contained, and from the end of which the bands may be cut off as required. This tube when made is wound upon a reel, from which it is led to the 5 wedge W', for opening it from a flat tube into a rectangular one, then drawn over the shuttle under the rollers R³, then between roll R⁴ and rollers R⁵, then conducted along to and between the feed-rollers and rollers R⁸ and R⁹, 10 and by these is pushed forward to the end of tube T, where it is cut off into bands, as required, by a mechanism which I will now describe.

A⁴ is a frame, which is preferably secured 15 to bed A², but which might be placed on bed A, if desired. This frame has a large circular opening wherein is fitted the cutter-carrying ring A⁵, which ring surrounds the tube T, as shown best in Figs. 4, 5, and 6. That ring is 20 held in place by a circular gib, A⁶, and is rotated by means of teeth T¹, formed thereon and gearing into the spur-wheel G³. The ring A⁵ is bored to receive a short shaft, S⁴, for carrying the cutter-arm A⁷. This arm at one end 25 is provided with a stud, S⁵, for carrying the rotary cutter C⁴, having a cylindrical part, C⁵, upon one side thereof, a spring, S⁶, being provided to keep this cutter against said arm, except when it is in use cutting off a band, as 30 shown in Fig. 13. At its other end this arm is formed into a cam-shaped hook, H, which, by coming against the sliding stop H², performs the double office of holding the cutter C⁴ away from tube T and preventing the further rotation of ring A⁵, holding it in the position shown by dotted lines in Fig. 6. When 35 the stop H² is slid out from within the hook H by a cam provided for that purpose, the shuttle being in the proper position and the paper tube projecting the width of one envelope-band beyond the end of tube T, the arm A⁷ is then swung upon shaft S⁴ by means of a spring or equivalent device (not shown) until the cylindrical part C⁵ of the rotary cutter 40 strikes the side of the said tube T in position longitudinally. (Shown in Fig. 13.) At the same instant the ring A⁵ is started revolving, the spring referred to all the while keeping the cutter against the tube T, which tube is 45 immediately moved forward to the position shown in Fig. 4, pressing against cutter C⁴, which cutter then acts as a shear to sever the paper at the end of said tube. This being done, the several parts are returned to their 50 previous positions preparatory to the further operations hereinafter described.

I have now given, embodied in the preceding part of this specification, a description of the construction and functions of all that which 55 I consider an essential part of my present invention, together with a description of the more immediate accessories to the same; but it is obvious that, in order to render those mechanisms operative, some suitable driving machinery is required. This may be any arrangement of shafts, cams, levers, and gearing, or of other parts suitable to produce the

desired movements of the essential parts of the machine, and it is within the capacity of any mechanic skilled in this class of machinery to design the same. For these reasons I do not in my claims limit the combinations to driving machinery of any particular form, as I may use any form thereof adapted or convenient for the purpose. Notwithstanding 75 this, however, and in order to more clearly illustrate my invention and its operation, I have shown one arrangement of driving machinery, which may be taken as the type of a class, and which I will now describe. 80

S is the driving-shaft of the machine, receiving continuous rotary motion by means of a pulley, P², on one end thereof, and near its other end having the pulley P', hereinbefore referred to, for driving the escapement mechanism. This shaft is supported in any suitable bearings which may be formed on bed A², substantially as shown in Figs. 1, 2, 3, and 6, and it is provided with a friction-disk, D³, keyed thereto by key K, Fig. 11, for the purpose of 85 communicating rotary motion to sleeve S', this being accomplished by means of a flange, F, fixed to said sleeve, flange F', screws F², and friction-washers F³, these parts together 90 constituting a well-known form of frictional 95 driving mechanism.

G⁵ is a gear loosely fitted upon sleeve S', which is driven therefrom by means of a frictional driving device similar to that just described, consisting of a flange, F⁴, which is 100 formed on said sleeve, flange F⁵, nut F⁶, and friction-washers F⁷. This friction device must be tightened sufficiently to drive the cutter-carrying ring A⁵, but not so much as to overcome the power of the first one, as that has to 105 drive the cam-shaft while said ring is stopped. The gear G⁵ meshes with one, G⁴, which is fixed to the gear G³, before referred to, these latter gears being supported by and revolving on a stud, S⁷, which is fixed into a lug extending 110 from frame A⁴, as shown best in Fig. 6.

S² is the cam-shaft, which is supported in bearings similar to those supporting shaft S, and is driven from sleeve S' by means of a gear, G⁶, on said shaft, which meshes with a 115 pinion, G⁷, on said sleeve.

C⁶ is a cam on that shaft for operating the sliding stop H², and it is provided with an abutment, B⁸, against which the end of rod R acts to arrest the motion of the cam-shaft at the 120 moment when the tube T is in proper position to receive a packed bunch of envelopes from box Q, this position being that shown in Fig. 18. It will be remembered that this rod R is operated through lever L from slide J, so as 125 to allow the cam-shaft to start at the moment when the said bunch is driven into said tube. Said rod R is to be provided with an ordinary spiral or equivalent spring, (not shown,) so connected to the frame as to move the rod toward the left hand in Figs. 1 and 2, to engage with the abutment B⁸. Thus the starting and stopping of said shaft are both controlled 130 through that rod.

C is a cylinder or cam in which is formed two cam-grooves, C² and C³. Groove C² acts through roll O and bracket B⁴ to operate slide M², said bracket being secured to frame N³ on 5 said slide. Groove C³ acts through roll O' on stud O² and slide S⁸, to operate the driving-roller R⁴, which operates the piston T', as hereinbefore described. These two cam-grooves are to be made of a form adapted to impart 10 the required movements to the slides M² and S⁸.

The operation of my envelope counting, packing, and banding machine is as follows: The envelopes are delivered from the folding-machine, usually from the endless apron there- 15 of, to the point N in front of plunger D. This plunger then moves forward, driving the envelope into box Q, as shown at N², Fig. 8, passing, en route, under the hooks I, thereby operating the pallet I², and allowing the stop 20 wheel W to move forward one division, as hereinbefore referred to. These operations continue until a bunch of the required size—usually twenty-five—has been packed, when the notch V allows the slide J to make its 25 stroke and drive the bunch E out of box Q into tube T, which tube then stood, as shown in Fig. 18, ready to receive it. At the completion of said stroke of slide T the parts stand in the position shown in Fig. 19, the bunch 30 being entirely inclosed within the tube, and the entire shuttle, together with that tube being inclosed within a paper or other tube, T⁴, from which the bands B⁵ are to be cut off. The slide M² now carries the shuttle back to 35 the position shown in Fig. 20, when the ratchet J⁵ begins to act to turn the feed-rollers R⁶, as before described, so that as the slide moves to its position in Fig. 21 the paper will be fed out over the end of tube T, as shown in this 40 figure. The end of this tube now stands relative to cutter C⁴ longitudinally, as shown in Fig. 13. Cam C⁶ now withdraws stop H² from hook H, the roller C⁵ drops onto the tube, and the ring A⁵ begins to rotate. Tube T is 45 now immediately carried forward to its position in Fig. 22, and the cutter, which then rests against the end of it, as in Fig. 4, passes two or three times around the tube, cutting off a band, B⁵, as shown in Fig. 23. The cam 50 C⁶ then returns stop H², which lifts the cutter from the tube and stops the rotation of ring A⁵. The piston T' is now pushed forward, driving the banded bunch out of the tube, as shown in Fig. 24, letting it fall out of the way, 55 when the parts are moved into the position shown in Fig. 25, which are the same as those in Fig. 18.

It is not necessary to the proper operation of my new banding mechanism that the bunch 60 of articles to be banded shall have been counted or packed by the mechanism which I have described for those purposes; and any other suitable devices may be substituted for them in combination with my said banding mechanism. I may use a counting mechanism 65 with or without a registering mechanism, such as shown and described in United States Pat-

ents No. 177,048 or No. 248,564, to which reference may be had; and I may use a packing apparatus substantially like that described in 70 United States Patent No. 66,876, to which reference may be had.

The tubes T⁴, Figs. 18 and 25, which are to be cut up into bands, are to be formed upon suitable tube-machines—such as used in the 75 manufacture of paper bags—and kept in stock ready for use. This method of making the bands by cutting them off from a tube as they are wanted avoids the use of gum in a banding-machine and all the annoyances arising 80 therefrom, such as spattering the gum onto the envelopes or the sticking of the bands to the bunch of envelopes, owing to the imperfect lapping of the band. Besides this the bands can be more perfectly stuck together when 85 that is done in a good tube-machine. The cutter C⁴ is not necessarily a rotary one, but it may be rigidly fixed to arm A⁷, or even formed integral therewith; but I prefer the construction shown, because, in my opinion, it 90 operates more effectually and with less wear.

In this application I make no claim to the method of banding envelopes carried out by the improved machine hereinbefore described, having described and claimed said method in 95 a separate application, which I am about to file.

Having thus described my invention, I claim—

1. The combination, in an envelope-counting mechanism, of a packing-box adapted to receive envelopes, means, substantially as described, for putting envelopes into said box one at a time, a plunger, substantially as described, adapted to push said envelopes laterally in said box, an intermittently-moving stop constructed to arrest the action of said plunger during the packing of a given number of envelopes, and escapement mechanism, substantially as described, operating said stop 105 from the envelopes passing into the box, substantially as set forth.

2. The combination, in an envelope-counting mechanism, of a box, Q, plunger D, and the hook or arm I, having thereon a pallet, I², 115 wheels I³ and W, gearing connecting said wheels, and plunger J, substantially as set forth.

3. The combination of box Q, plunger D, plunger J, and tube T, substantially as set 120 forth.

4. The combination, in an envelope counting and packing mechanism, of shuttle M, having tube T, means, substantially as described, for supporting said shuttle, and 125 band cutting-off mechanism, arranged and operating substantially as set forth.

5. The combination, with a suitable framework, of ring A⁵, shaft S⁴, arm A⁷, carrying stud S⁵, cutter C⁴, constructed to revolve and 130 slide on said stud, and spring S⁶, all arranged to operate substantially as set forth.

6. The combination, with tube T, of a frame, as A⁴, ring A⁵, shaft S⁴, arm A⁷, having the

rotary cutter C⁴ and hook H and stop H², whereby said cutter is first swung away from said tube and then said ring held from rotation, substantially as set forth.

5 7. The combination of a frame, as A⁴, ring A⁵, shaft S⁴, arm A⁷, having a cutter, C⁴, and hook H, stop H², and cam C⁶, substantially as set forth.

8. The combination of tube T, ring A⁵, arm 10 A⁷, having stud S⁵, rotary cutter C⁴, having rollers C⁸, and spring S⁶, substantially as set forth.

9. The combination of plunger J, having a pin, J', lever L, rod R, and shaft S², having a

part, as C⁶, with a lug, B³, substantially as 15 set forth.

10. The combination of a shuttle, M, having tube T, slide M², having devices, substantially as described, for carrying said shuttle, piston T', having rollers R³, slide S⁸, the cam C, provided with cam-grooves C² and C³, connections from one of said grooves to slide S⁸ and from the other to slide M², substantially as set forth.

FRANCIS H. RICHARDS.
